UNITED STATES PATENT OFFICE.

GEORGE R. THOMPSON, OF BROCKTON, MASSACHUSETTS.

CAR-COUPING.

SPECIFICATION forming part of Letters Patent No. 488,586, dated December 27, 1892.

Application filed May 2, 1892. Serial No. 431,526. (No model.)

To all whom it may concern:

Be it known that I, GEORGE R. THOMPSON, of Brockton, in the county of Plymouth and State of Massachusetts, have invented certain 5 new and useful Improvements in Car-Couplers, of which the following is a specification.

It is the object of my invention to provide improved means for uncoupling or unshackling cars without the necessity of going between the cars, or of undergoing any of the dangers heretofore incident to the coupling and uncoupling in the manipulation of the link-and-pin and similar coupling devices.

My invention consists of these several improvements hereinafter described and claimed, reference being had to the annexed drawings, and the letters marked thereon, forming a part of this specification, the same letters designating the same parts or features, as the case 20 may be, wherever they occur.

In the drawings: Figure 1 is a perspective view of a draw-bar and buffer shown as attached to a car body constructed in accordance with my invention. Fig. 2, is a top 25 plan view of two draw-bars coupled equipped with my improvements. Fig. 3, is a bottom plan view of the same. Fig. 4, is a horizontal sectional view of my invention. Fig. 5, is a similar view showing the two draw-heads 30 coupled. Fig. 6, is a side elevation of my invention. Fig. 7, is a perspective view of a link used in connection with my improvements. Figs. 8, and 9, are sectional detail views showing the manner of latching and 35 unlatching the uncoupling means.

In the drawings: *a* designates the front of a car body with which a draw-bar or head *b* is connected in the usual way.

c is the buffer arranged to slide longitudinally in the draw-bar, a spring *d* surrounding the buffer bar and acting at one end against a collar or bearing *e* fixed in the draw-bar and resting at its other end against a shoulder or offset *f* on the buffer bar, serving to hold the buffer normally outward in the draw-bar. The drawhead *b* is provided with a chamber *f* at one side of the buffer *c* in which upon a vertical pin *g* is pivoted a link *h*, provided on its outer end with a vertical slot *i* adapted to 45 receive the coupling pin *j* horizontally arranged in the opposite drawhead. The drawhead is provided on the opposite side of the

buffer with a slot *k* of such form as to receive therein the projecting end of the link *h* pivoted in the opposite drawhead. The coupling 55 pin *j* passes through the drawhead from side to side, and is connected at its outer end, as at *l* with one end of a link *m*, the opposite end of which is rigidly attached to a rod *n* arranged to slide in suitable bearings *o* beneath 60 the drawhead. The rod *n* extends out from opposite sides of the drawhead to the sides of the car, and is provided on each end with suitable handles *p* to adapt it and its attached coupling pin to be manipulated without the 65 necessity of going between the cars.

q is a spring surrounding the rod *n* and resting at one end against a bearing *o* and at the other against collar *r* attached to the rod, and acting with a tendency to force the 70 coupling-pin *j* inward through the slot *i* of the link *h* as will be understood by an inspection of the drawings. The coupling pin *j* is reduced in that part which operates in the link *h* and that part of the drawhead at the 75 side of the buffer in which the vertical slot *f* is constructed so as to form a shoulder *s* on the said pin.

t is a gravity latch pivoted in the drawhead, and adapted when the cars are coupled or 80 when the buffer is not out to its utmost limit and the coupling pin is withdrawn from the position in which it is represented in Fig. 5 to that in which it is shown in Fig. 4, to fall behind the shoulder *s* and hold the said pin out 85 against the stress of the spring *q*.

u is a pin projecting laterally from the side of the buffer bar, and so arranged that when the buffer is forced outward the pin *u* will ride upon the latch *t* and force it out of engagement with the shoulder *s*. 90

In the use of the invention, supposing the cars to be coupled as is represented in Fig. 5, and that it is desired to uncouple the same, the brakeman or other person taking hold of 95 the handle *p* of rod *n*, will pull or push upon said rod, as the case may be, against the stress of the spring *q* moving the coupling pin *j* back from engagement with the link *h* and allowing the pivoted gravity latch *f* to fall behind the shoulder *s* of the coupling pin in which position the rod *n* may be left. As soon as the cars separate, the buffer will be forced outward to its extreme limit, the pin *u* 100

acting as before explained, to disengage the latch from the coupling pin, and the buffer bar itself coming behind the shoulders to hold the coupling pin back, as shown in Fig. 4. 5 With the parts in this position, and two cars coming together, the link *h* on the draw-head of each will enter the slot *f* of the opposite draw-head, and the buffers being forced inward, and their bars disengaged from the 10 shoulder *s* of the coupling pins, the latter will be actuated by the springs *g* so as to enter the slots *i* and automatically effect the coupling of the cars. The links *h* are arranged to swing upon their pivot pins *g* to an extent 15 sufficient to compensate for lack of exact alignment of the draw-bars, and the coupling slot *h* is sufficiently long to allow for all variation in the plane at which draw-heads of adjacent cars may stand.

20 It will be seen that with my invention no necessity exists for going between the cars to couple and uncouple the same, and that uncoupling can be accomplished from either side of the car with but a single movement of 25 the hand.

No parts exist that can readily get out of order, while the invention is exceedingly simple in construction and operation.

Having thus described the nature of my in-

vention, and explained a way of constructing 30 and using the same, though without attempting to set forth all of the forms in which it may be made, or all of the modes of its employment, I declare that what I claim is:—

1. A car coupling comprising in its construction, a drawhead provided with a groove *k*, a link *h* provided with the slot *i* pivoted in the drawhead, a coupling pin, a spring-pressed rod having bearings on the drawhead and connected with the coupling-link, and a gravity latch to lock the pin back when withdrawn by means of the rod against the stress of its spring, as described. 35

2. In a car coupling, the combination, with the drawhead, provided with the groove *k*, and having the link *h* pivoted therein, of the coupling pin *l* provided with the shoulder *s*, the gravity latch adapted to engage the said shoulder, and the spring-pressed rod *n* connected with the coupling pin, as described. 40 45

In testimony whereof I have signed my name to this specification, in the presence of two subscribing witnesses, this 6th day of April, A. D. 1892.

GEORGE R. THOMPSON.
